VALVE

Homer E. Malone, Minneapolis, Minn., assignor to
 Minneapolis-Honeywell Regulator Company,
 Minneapolis, Minn., a corporation of Delaware

Application December 24, 1934, Serial No. 758,952

3 Claims. (Cl. 236—42)

This invention relates to valves and more particularly to those types of valves that are capable of automatic and manual operation.

An object of this invention is to provide a valve 5 of the character described wherein a single means is provided for regulating the automatic operation of the valve and to move the valve to open and closed positions.

Another object is to provide a valve structure 10 cooperable with associated valve seats wherein the valve structure is moved towards one of the seats by a condition responsive device against the action of an adjustable biasing means and wherein manual means are provided for adjusting the biasing means and for moving the valve towards the other seat.

A further object is to provide a novel adjusting device for regulating the automatic operation of a valve and for moving the valve to held opened 20 or held closed positions, said adjusting device comprising a member that is moved through successive steps to control the action of the valve.

Other objects and advantages will become apparent to those skilled in the art upon reference 25 to the accompanying specification, claims and drawing in which:

Fig. 1 is a vertical sectional view through the valve of my invention;

Fig. 2 is a top plan view of the valve and showing the sequence of operation thereof;

Fig. 3 is a horizontal sectional view taken substantially on the line III—III of Fig. 1, and

Fig. 4 is a horizontal sectional view taken substantially on the line IV—IV of Fig. 1.

The valve comprises a casing 10 having a transverse partition 11 therein which divides the interior portion of the casing 10 into a lower inlet chamber 12 and an upper outlet chamber 13. The transverse partition 11 is provided with a 40 port opening 14 to establish communication between the inlet chamber 12 and the outlet chamber 13. Located adjacent the upper extremity of the port opening 14 is an annular seat 15 and located adjacent the lower extremity of port opening 14 is another annular seat 16. Fluid to be valved is supplied to the inlet chamber 12 in any suitable manner, not shown, and the valved fluid is drawn off from the outlet chamber 13 in any suitable manner, not shown.

A flanged member 25 having a longitudinal passage therethrough is secured and held in fluid-tight relationship with a collar member 27 by means of a nut 26 being screw-threaded on the flanged member 25. The collar member 27 is in turn screw-threaded into the lower portion of the

casing 10 and a fluid tight joint is afforded in this connection by means of an annular seat 28 integral with the casing 10 engaging the collar member 27.

A tube 29 is pressed and soldered into the flanged member 25 and the lower portion of the tube 29 is closed in a fluid-tight manner by means of a cap 30 soldered in the tube 29. A reinforcing tube 31 is rigidly secured within the tube 29 and a baffle member 32 having a restricted opening 10 therein is in turn rigidly secured in the reinforcing tube 31. The tube 29 is adapted to receive a charge of volatile fluid in the manner to be pointed out hereinafter.

Secured to the upper end of the flanged member 25 in coaxial alignment with the tube 29 is a guide member 33, having an opening therethrough and having radially extending notches 40 therein. Also secured in fluid-tight manner to the upper portion of the flanged member 25 is one end of a bellows 41. The other end of the bellows 41 is secured in a fluid-tight manner to a movable enclosure member 42. The movable enclosure member 42 has a downwardly extending boss 43 with a downwardly extending passage 44 located therein. An abutment screw 45, having an enlarged head is screw-threaded into the lower portion of the boss 43. A spring 46 surrounds the abutment screw 45 and is adapted at certain times to engage the boss 43 of the movable enclosure member 42. The movable enclosure member 42 is also provided with an upwardly extending boss 47 which has a vertical passage 48 in engagement with the downwardly extending passage 44 of the boss 43. The vertical passage 48 of the upper boss 47 is provided with a removable screw plug 49.

By removing the removable plug 49, a charge of suitable volatile fluid may be inserted in the vertical passage 48 and may flow through the downwardly extending passage 44 into the bellows 41 and down through the guide member 33 into the tube 29. When the charge of volatile fluid has been inserted in the manner described, the plug 49 is inserted in the passage 48 to seal the same. Upon an increase in temperature acting on the tube 29, the volatile fluid contained therein will volatilize and cause expansion of the bellows 41 and consequent upward movement of the movable enclosure member 42. A decrease in temperature acting on the tube 29 will cause condensation of the volatile fluid contained therein to permit contraction of the bellows 41 and consequent lowering of the movable enclosure member 42. In case the enlarged head of the abutment

screw 45 should engage the guide 39, passage of volatile fluid through the guide 39 will be permitted by the radial slots 40 located in the lower extremity of the guide 39.

5. Although I have disclosed a condition responsive means in the form of a temperature responsive means utilizing volatile fluid for moving the movable enclosure member 42, it is within the contemplation of this invention that the movable 10 enclosure member may be moved by other means and responsive to other conditions. For example, the enclosure means 42 could be moved in response to changes in pressure instead of temperature and the pressure changes could easily be 15 transmitted into the bellows 41 by a pipe or like means.

The upper boss 47 is exteriorly screw-threaded to receive an interiorly screw-threaded member 50. A resilient disc member 51 which is rigidly 20 secured in a fluid-tight manner to a valve disc 52 is adapted to be clamped between the screw-threaded member 50 and the movable enclosure member 42 so that upon upward and downward movement of the movable enclosure member 42, 25 the valve disc 52 will also be moved upwardly and downwardly. The valve disc 52 is adapted at certain times to engage the lower valve seat 16 of the port opening 14 and the resilient disc member 51 insures a good seating action. It will be noted 30 at this point that the area of the bellows 41 is substantially the same as the area of the valve disc 52 whereby the inlet pressure acting on the valve disc 52 is balanced to prevent upward movement of the valve disc 52 by the inlet pressure 35 acting thereon.

A second movable enclosure member or valve, located in the outlet chamber 13, is designated at 53 and it has an upwardly extending bore 54 which is adapted to receive an upwardly extending 40 extension 55 of the screw-threaded member 50. The upper movable enclosure member 53 is adapted to engage a shoulder formed on the screw-threaded sleeve 50 by the upwardly extending extension 55. The movable enclosure member 53 is provided with an upwardly extending 45 abutment boss 56 in which the bore 54 is located for purposes to be described more fully hereafter. The movable enclosure member 53 acts as a valve member and engages at predetermined times the upper valve seat 15 of the port opening 14.

The lower end of a bellows 58 is secured to the movable enclosure member or valve 53 in a fluid-tight manner and the upper end of the bellows 58 is also secured to a guide member 59 in a fluid-tight manner. The bellows 58 is of substantially 55 the same area as the valve or movable enclosure member 53 whereby the outlet pressure acting on the valve or movable enclosure member 53 is balanced to prevent downward movement of the valve 53 by the outlet pressure acting thereon. The guide member 59 is provided with a flange 60 which overlies the casing 10 and the guide member 59 is held rigidly to the casing 10 by means of a cap member 61 being screw-threaded 60 on the casing 10 and clamping therebetween the flange 60.

The guide member 59 is provided interiorly thereof with a hexagonal opening 62 which is adapted to receive a hexagonal abutment member 63 as clearly shown in Fig. 4. By reason of 70 this hexagonal relationship, the hexagonal abutment member 63 is permitted to move longitudinally in the guide member 59 but rotation thereof is prevented. A spring 64 extends between the abutment member 63 and the movable

5. enclosure member or valve 53 and guided by the upwardly extending boss 56 to at all times urge the enclosure member 53 in a downward direction towards its associated valve seat 15. The spring 64 is so selected that the effort exerted by it is greater than the pressure of the fluid existing in the chambers 12 and 13 whereby the movable enclosure member 53 is always held in engagement with the shoulder of the screw-threaded member 50. By reason of this, the movable enclosure member or valve 53 is held in a fixed relation with respect to the valve disc 52 whereby these two elements are moved in unison. The spring 64 is adapted to resist the upward movement of the movable enclosure members by 15 volatilization of the volatile fluid contained in the tube 29.

The abutment member 63 is provided with slots 65 which receive downwardly extending lugs 66 of a screw 67. By reason of these slots 65 in the 20 abutment member 63 and the lugs 66 rotational movement of the screw 67 is prevented. The screw 67 has a passage extending therethrough, the lower portion of which is screw-threaded and adapted to receive an adjusting screw 68. The 25 adjusting screw 68 abuts against the abutment member 63 and by moving this adjusting screw 68, the abutment member 63 is moved with respect to the screw 67 to adjust the tension placed in the spring 64. This provides convenient means 30 for initially calibrating the spring 64.

The exterior screw threads of the screw 67 engage and coact with screw-threads formed in a member 69 which is in turn rigidly secured in a nut 70. By making the screw-threads on the 35 member 69 separable from the nut 70, the cost of manufacturing is thereby reduced since the parts are more easily machined. The nut 70 is provided with an outwardly extending flange 71 which abuts against the guide member 59. The 40 nut 70 is held in place for rotation by means of a screw-threaded collar 72 which is screw-threaded in the cap member 61 and which overlies the flange 71 of the nut 70. Located between the screw-threaded collar 72 and the flange 71 is a 45 friction bearing disc 73 which permits easy rotation of the nut 70 with respect to the stationary screw-threaded collar 72. By rotating the nut 70, the screw 67 is moved upwardly and downwardly to place more or less tension in the 50 spring 64 to determine at which temperature the force of the volatile fluid contained in the tube 29 will overcome the force of the spring 64 to move the valve disc 52 to its seat 16 to close the port opening 14.

The nut 70 is provided with an upwardly extending boss 75 to which is rigidly secured a collar member 77 as by means of splines 76. The collar member 77 is in turn rigidly secured as by means of splines 78 to a reinforcing member 79 60 which is molded into a composition handle 80. The handle 80 is provided with a pointer 81. The handle 80 is held in place on the nut 70 by means of a screw 82. By turning the handle 80, the nut 70 is also turned to give longitudinal movement to the screw 67. By removing the screw 82, the screw 68 may be adjusted as by means of an Allen wrench to calibrate the spring 64.

Clamped between the cap member 61 and the 70 screw-threaded collar 72 is an annular member 83 to which is secured a cover 84 by means of screws 85. Secured to the upper surface of the cover 84 by means of rivets 86 is a dial plate 87 which coacts with the pointer 81 of the handle 75.

80 to visually indicate the position of the parts located within the valve.

As shown in Fig. 1, the valve disc 52 is in engagement with its valve seat 16 thereby preventing flow of fluid from the inlet chamber 12 to the outlet chamber 13. Upon a decrease in temperature acting on the tube 29, the volatile fluid contained therein will decrease the pressure existing in the bellows 41 to permit expansion of the spring 64 to move the valve disc 52 away from its seat 16 to permit communication between inlet chamber 12 and outlet chamber 13. Excessive downward movement which would normally be caused by a decrease in temperature is prevented by downwardly extending boss 43 engaging the relatively strong spring 46. When the boss 43 so engages the spring 46, the valves 52 and 53 are equally spaced from their respective seats 16 and 15 to give maximum port opening between the inlet chamber 12 and the outlet chamber 13. Upon an increase in temperature as determined by the tension in the spring 64, the volatile fluid in the tube 29 will volatilize to create a pressure within the bellows 41 to cause upward movement of the valve disc 52 against its seat 16.

The position of the handle 80 as shown in Fig. 2 and designated "low temperature" corresponds to the position of the parts as shown in Fig. 1 wherein the spring 64 is in its longest adjustment to afford least resistance to upward movement of the valves 53 and 52. In such a position, only a relatively low temperature acting on the tube 29 is required to overcome the spring 64 to move the valve 52 to a closed position.

By turning the handle 80 in a counter-clockwise direction, as viewed in Fig. 2, toward the warmer direction, the nut 70 will be turned a like amount to cause downward movement of the screw 67. This downward movement of screw 67 causes an increase in compression in the spring 64 whereby a greater volatile fluid force acting on the bellows 41 and consequently a higher temperature is required to overcome the spring 64 to move the valve disc 52 to its seat 16. When the handle 80, as viewed in Fig. 2, is so moved that the pointer 81 thereof falls along the "high temperature" line, the screw 67 will be moved downwardly in such an amount that the lugs 66 will just engage the upwardly extending boss 56. When the screw 67 has been moved to this position, the spring 64 is compressed its greatest amount thereby requiring the highest temperature acting on the tube 29 to move the valve 52 to its seat. From the above, it is seen that when the handle 80 is so positioned that the pointer 81 thereof is located between the "low temperature" indication and the "high temperature" indication automatic control of the valve is obtained and the valve will be opened and closed according to temperature changes acting on the tube 29 which temperature changes are determined by the position of the handle 80.

Further counter-clockwise movement from the "high temperature" indication as seen in Fig. 2 causes further downward movement of the screw 67. Since the lugs 66 formed integral with the screw 67 are in engagement with the upwardly extending boss 56 of the movable enclosure member 53, the movable enclosure member or valve 53 will be moved in a downward direction. This movement causes the movable enclosure member or valve 53 to move toward its seat 15 and the valve 52 away from its seat 16.

When the handle 80 is so positioned that the

pointer 81 thereof coincides with the "held open" indication of Fig. 2, the valves 53 and 52 will be moved downwardly to such an extent that they will be equally spaced from their respective seats 15 and 16. When the valves 53 and 52 are moved to this position, the lower boss 43 of the movable enclosure member 42 engages the spring 46 to resist downward movement beyond this point. In this manner, the valve as a whole is held in an open position and variations in temperature effecting the tube 29 will have no effect to move the valve as a whole out of this position.

Further counter-clockwise movement of the handle 80 from this position will cause further downward movement of the movable enclosure member or valve 53 and valve 52. When the handle 80 is rotated in a counter-clockwise direction sufficiently far so that the pointer 81 thereof aligns with the "held closed" indication of Fig. 2, the valves 53 and 52 will be moved downwardly to such an extent that the valve 53 will engage the valve seat 15. This further downward movement of the valves 53 and 52 is permitted by compressing the spring 46. When the valves are moved into this extreme downward position, the passage 14 between the inlet chamber 12 and the outlet chamber 13 is closed by the valve 53 engaging the valve seat 15 and when the parts are in this position the valve as a whole is held closed and any temperature variations effecting the tube 29 will have no effect to move the valve out of this position.

From the above, it is seen that I have invented a valve that is automatic in operation and that may be manually moved to a "held open" position or a "held closed" position and wherein a single means is provided whereby the valve may be moved to a "held open" or "held closed" position or whereby the temperature setting of the valve may be adjusted to cause automatic operation of the valve at various conditions or more specifically degrees of temperature.

It is obvious that many modifications may be apparent to those skilled in the art and consequently this invention is to be limited only by the scope of the appended claims and prior art.

I claim as my invention:

1. An automatic valve comprising a valve chamber, a partition having a port therein and separating said chamber into inlet and outlet passages, said port having valve seats on each side of said partition, a valve member comprising a pair of rigidly connected valve elements disposed on opposite sides of said partition and cooperating with said valve seats, condition responsive means for causing movement of said valve member in accordance with variations in the condition to which said device is responsive between a position wherein one of the valve elements is in engagement with the corresponding valve seat and a position wherein neither of the valve elements is in engagement with the valve seats, means biasing the valve member towards the last named position, a movable member, and means responsive to movement of said member in a single direction to first increase the force of said biasing means, to next positively hold the valve elements in a position wherein neither element is in engagement with its valve seat and to lastly hold the other of said valve elements positively in engagement with its valve seat.

2. An automatic valve comprising a valve chamber, a partition having a port therein and separating said chamber into inlet and outlet passages, said port having valve seats on each side

of said partition, a valve member comprising a pair of rigidly connected valve elements disposed on opposite sides of said partition and cooperating with said valve seats, condition responsive means for causing movement of said valve member in accordance with variations in the condition to which said device is responsive between a position wherein one of the valve elements is in engagement with the corresponding valve seat and a position wherein neither of the valve elements is in engagement with the valve seats, means biasing the valve member towards the last named position, and a rectilinearly movable member cooperating with said biasing means and said valve member to successively increase the force of the biasing means, to positively hold the valve elements in a position wherein neither element is in engagement with its valve seat, and to hold the other of said valve elements positively in engagement with its valve seat in response to movement of said member in a single direction.

3. A device comprising valve casing means, valve seating means, rigidly connected valve elements cooperating with said valve seating means, condition responsive means for causing movement of said valve elements in accordance with variations in the condition to which said device is responsive between positions wherein one of said valve elements engages said valve seating means and a position wherein said valve elements do not engage said valve seating means, means biasing said valve means to said last named position, a movable member and means responsive to movement of said member in one direction to increase the force of said biasing means, to next positively hold the valve elements in a position not in engagement with said valve seating means, and to lastly hold the other of said elements positively in engagement with said valve seating means.

HOMER E. MALONE. 20
